his attorney.

UNITED STATES PATENT OFFICE.

WILLIAM G. FISCHER, OF CINCINNATI, OHIO.

FLUE-TOP.

1,297,134.

Specification of Letters Patent. Patented Mar. 11, 1919.

Application filed April 4, 1917. Serial No. 159,721.

To all whom it may concern:

Be it known that I, WILLIAM G. FISCHER, a citizen of the United States of America, and a resident of Cincinnati, in the county 5 of Hamilton and State of Ohio, have invented a certain new and useful Improvement in Flue-Tops, of which the following is a specification.

This invention relates to caps or tops for 10 smoke-flues and, more particularly, such flues as are used on railway-cars and other moving structures or vehicles that travel at various or high speeds. In the onward movements of said traveling structures, a 15 current of wind of greater or less force is produced and results in forcing down the flue of a heater within the structure the smoke and other products of combustion generated within the heater, to the annoyance of those within, as well as to the injury or damage of the walls within. To 20 remedy said evil and to produce a device that will assure the free passage of said smoke and other gaseous products of combustion from the exit or top of the flue is the 25 object of my invention herein, the details of structure, as well as the mode of operation being hereinafter fully described and then more particularly pointed out in the claims 30 that follow.

In the accompanying sheet of drawings, Figure 1 is a fragmentary perspective view showing the upper fore-end of a traction-car having my improved flue-top in place there- 35 on; Fig. 2, a front elevation of the flue-top taken by itself; Fig. 3, a side elevation of the said flue-top shown in Fig. 2; Fig. 4, a central longitudinal section of the flue-top shown in normal position and as duly at- 40 tached to the upper end of the smoke-flue, the latter being shown broken off; and Fig. 5, a central transverse section of Fig. 4.

1 indicates the roof of a traction-car or that of any other moving structure or vehicle in connection with which my invention herein is particularly adapted for use and especially because of the wind that is ordi- 45 narily forced down the flue in the advance movement of the structure and much greater 50 when such movement is at a high speed.

2 indicates the upper end of a flue or pipe that is shown broken off but extending up- 55 wardly from a fuel-burning heater within the structure 3. The pipe-section 2 is a cy- lindrical one, as customary, and said upper end thereof projects beyond the surface of

roof 1 to be telescoped by the vertical pipe- 60 section portion 4 of my improved cap or top. Registering holes 5 are made diametrically through the telescoped portions of the flue 65 2 and pipe-section 4 for accommodating a transverse wire 6, the latter being bent at its opposite ends 7 so as to connect or fasten the said telescopic portions and to prevent their turning on each other.

8 indicates a horizontal pipe-section having a V-joint connection 9 with the upper end of the vertical pipe-section 4, and 10 is an oscillating shunt or valve-plate loosely supported, between its opposite ends, 70 on a transverse wire 11 that is similar to wire 6, the said wire 11 also having its opposite ends extending beyond the outer face of the horizontal pipe-section 8 and bent over, as shown at 12 to prevent the escape of the 75 transverse wire 11 from bearing-support and, at the same time, permitting the valve-plate 10 to be readily replaced when desired and to avoid riveting the opposite ends of 80 said transverse wire 11.

It will be observed, in Fig. 5, that the valve-plate 10 is of egg-shape and that its cross-wire pivotal-support is somewhat above its horizontal center so as to provide a deeper smoke-diverting portion below the 85 horizontal bearing in the lower portion of the pipe-section 4, sufficient surface being provided above the bearing 11 for the contact of the wind in setting the valve-plate in position for the desired escape of the smoke 90 and gases from the flue when the wind is coming from either side-quarter.

In practice, the cap or top is attached in position on the upper end of the flue 2 so that the horizontal section 8 lies trans- 95 verse to the length of the roof of the moving structure or vehicle, the opposite open ends or exit-orifices of said horizontal pipe- 100 section 8 facing said side-quarters of the wind and adapted to catch the wind from said side-quarters, especially when the moving structure is passing intersections of streets or on curves, or when the wind from said side-quarters is of greater force than that caused by the displacement of the on- 105 wardly-moving structure as it swiftly passes through the air. Thus, when a sudden gust of wind comes from a side-quarter it imme- 110 diately rocks the valve-plate so that the lower portion thereof tilts toward the wind and the upper portion thereof moves with the advancing wind, thereby diverting the

smoke from below into a free passage from the exit-orifice at the opposite end of the horizontal pipe-section 8, the lower portion of the valve-plate preventing any wind 5 passing downward into the flue and the crescent-shape opening now provided along the upper edge of the valve-plate, between it and the inner face of the upper arc of the said pipe-section 8, permitting the said gust 10 of wind to freely dispel itself onward and to cause more or less of a suction to augment the flow of the smoke from said exit-orifice. To further augment the flow of the smoke 15 from the flue-top, I provide an opening 13 in the upper portion of the valve-plate 10. This hole 13 also provides means for the ordinary circulation of air therethrough when the valve-plate is in normal perpendicular position and no transverse gust of 20 wind present in the cap or top of the smoke-flue.

15 indicates a semi-circular wing or fender projecting from each of the two exit-orifices or opposite open ends of the horizontal pipe-section 8 that forms the flue-cap proper. These wings or fenders 15 preferably flare outwardly, trumpet-fashion, with their convex faces disposed forwardly, or toward the front of the moving structure 30 or vehicle so that the wind is simultaneously diverted from both of said exit-orifices of the cap-proper 8 and the smoke and other gaseous products of combustion from the fire in the heater below can freely pass from 35 said exit-orifices, without any possible chance of back-draft within the flue to cause the smoke to retreat into the interior of the moving structure or vehicle to the discomfort of those within as well as to grime or 40 otherwise damage the inner walls or surfaces thereof.

In Fig. 3 is best shown how the opposite ends of each of the wings or fenders 15 are slightly flared at 16, such flaring 16 still 45 further causing the wind to depart from entrance into the exit-orifices of the flue-cap proper 8 and successfully diverting said wind away therefrom.

To still further facilitate the free passage 50 of the smoke from the flue I outwardly flare the said exit-orifices of the flue-cap proper 8, as shown at 17.

It will be observed, in said Fig. 3, also, that the opposite ends of each wing or

fender 15 are not in alinement with the perpendicular center of the flue-cap, the object thereof being to protect each upper edge of the said exit-orifices of the flue-cap as much as possible against the wind that is produced by the onwardly rushing car or vehicle and especially the natural tendency of the emitting smoke or gases is to arise or ascend and to naturally overlap said upper edges of the exit-orifices to be only retreated 60 backwardly into the flue unless the upper 65 ends of said wings or fenders are extended beyond the said perpendicular center of the cap. The arrangement of the other or lower ends of the wings or fenders at a point prior to reaching said perpendicular center 70 of the flue-cap tends to divert the wind from the exit-orifices downwardly before it can reach said exit-orifices or their lower edges and to prevent any chance for any upward 75 current or diversion of the wind created by the fast moving vehicle.

I claim:—

1. In a stationary top or cap for smoke-flues of vehicles, a vertical mounting pipe-section, a horizontal pipe-section or cap-proper extending in opposite directions from the top of the said vertical mounting pipe-section, semicircular substantially equal flaring wings or flanges extending from the opposite ends of said horizontal pipe-section, 80 and a vertical valve-plate having an opening in its upper end and pivotally supported just below said opening but centrally within said cap-proper and with its lower end of greater extended length than its said upper end whereby it projects downwardly into the said vertical pipe-section and is adapted for closing contact or engagement with the inner face thereof when swung in either direction from a normally perpendicular 90 position.

2. In a top or cap for smoke-flues of vehicles, a vertical pipe-section, a horizontal pipe-section or cap-proper surmounting said vertical pipe-section and extending in opposite directions therefrom, and semi-circular wings or fenders extending from the opposite exit-orifices or open mouths of said cap-proper with their convex faces extending in the direction of forward movement 105 of the vehicles.

WILLIAM G. FISCHER.
